UNITED STATES PATENT OFFICE.

CHRIS WEBER, OF HAVANA, NORTH DAKOTA.

TATTING-SHUTTLE-WINDING DEVICE.

1,170,586.

Specification of Letters Patent.

Patented Feb. 8, 1916.

Application filed February 12, 1915. Serial No. 7,339.

To all whom it may concern:

Be it known that I, CHRIS WEBER, a citizen of the United States, residing at Havana, in the county of Sargent and State of North Dakota, have invented certain new and useful Improvements in Tatting-Shuttle-Winding Devices; and I do hereby declare the following to be a full, clear, and exact description of the invention, such as will enable others skilled in the art to which it appertains to make and use the same.

My invention has for its object to provide a tatting shuttle winding device; and, to this end, it consists of the novel devices and combinations of devices hereinafter described and defined in the claims.

In the accompanying drawings, which illustrate the invention, like characters indicate like parts throughout the several views.

Referring to the drawings: Figure 1 is a plan view of the tatting shuttle winding device with a tatting shuttle applied thereto in working position, the spool from which the thread is wound onto the shuttle being indicated by means of broken lines; Fig. 2 is a side elevation of the parts shown in Fig. 1, some parts being broken away; and Fig. 3 is a view corresponding to Fig. 1, with the exception that the device is shown in a position to release the tatting shuttle, said shuttle being shown in section.

The numeral 1 indicates a U-shape metallic frame, the transverse portion of which is tempered to afford a spring that yieldingly draws the prongs of the frame toward each other. The end portions of the prongs of the frame 1 afford a pair of handles by which the device is held, and inward of these handles said prongs are bulged laterally outward to afford clearance for a tatting shuttle 2. In one side of the shuttle 2, and at the axis thereof, is formed a relatively shallow seat 3 adapted to receive a trunnion 4 rigidly secured to one of the prongs of the frame 1 and extending transversely between the said prongs.

Journalized in the other prong of the frame 1 and in a bracket 5 rigidly secured thereto is a hand crank 6 axially alined with the trunnion 4 and having a clutch 7. This clutch is removably seated in a pair of diametrically opposite perforations 8 formed in the body of the shuttle 2 on the opposite side from the seat 3. Obviously, the spring tension of the frame 1 yieldingly holds the trunnion 4 within the seat 3 and the clutch 7

within the seats 8, and by means of the crank 6 the shuttle 2 may be rotated on said trunnion within the frame 1. To remove the shuttle from the frame 1, it is only necessary to separate the prongs of said frame under their spring tension a distance sufficient to withdraw the trunnion 4 and clutch 7 from their respective seats in the shuttle 2.

A spool holder 9 and a thread tension device 10 are secured to the same prong of the frame 1 as the trunnion 4, but on the opposite side therefrom. As shown, the thread tension device 10 is constructed from a flat piece of spring metal in the form of a compound curve, between which tension device and the adjacent portion of the frame 1 the thread Y runs. An adjusting screw 11 is passed through the intermediate portion of this tension device and has screw thread engagement with the frame 1. To prevent rotation of the tension device 10 on the frame 1, the rear end portion thereof is reduced at 12 and passed through a perforation 13 in said frame. In the upper edge portion of the tension device 10, forward of the screw 11, is a forwardly and downwardly inclined slot 14 which affords a guide for the thread Y in passing from the spool Z, on the spool holder 9, to the tension device 10. From the guide 14 the thread Y is extended forward between the tension device 10 and the frame 1. The thread Y, from the tension device 10, is extended forward around the transverse portion of the frame 1 through an open guide 15 formed therein and attached to the body of the shuttle 1. The guide 15 is in direct alinement with the engaging surfaces of the spring prongs at each end of the shuttle 2, and under the rotation of said shuttle by the crank 6 the thread Y is drawn between these spring prongs and wound on the body of the shuttle 2.

What I claim is:

1. In a device for winding a tatting shuttle, the combination of a U-shape frame having handle forming prongs, and a crank journaled on said frame for rotating said shuttle therein, said crank adapted to be interlocked with said shuttle by the closing movement of said prongs and to be released therefrom by the opening movement thereof.
2. In a device for winding a tatting shuttle, the combination of a U-shape frame having normally spring opened handle forming prongs, and a crank journaled on said frame for rotating said shuttle therein, said

crank adapted to be interlocked with said shuttle by the closing movement of said prongs and to be released therefrom by the opening movement thereof.

5. In a device for winding a tatting shuttle, the combination of a U-shape frame having normally spring opened handle forming prongs, means for detachably journaling said shuttle to one of said prongs, and a

10 crank journaled in the other of said prongs and having a clutch adapted to be interlocked with said shuttle by the closing movement of said prongs and to be released therefrom by the opening movement thereof.

15 4. In a device for winding a tatting shuttle, the combination of a U-shape frame, a trunnion on one of the prongs of said frame, said shuttle being removably journaled on said trunnion, a crank journaled on the other 20 prong of said frame and having a clutch separately connected to said shuttle, said shuttle adapted to be removed from said trunnion and clutch by the separation of the prongs of said frame, and a thread tension 25 device on said frame.

5. In a device for winding a tatting shuttle, the combination of a U-shape frame, a trunnion on one of the prongs of said frame, said shuttle being removably journaled on 20 said trunnion, a crank journaled on the other prong of said frame and having a clutch separately connected to said shuttle, said shuttle adapted to be removed from said trunnion and clutch by the separation of the 25 prongs of said frame, a thread tension device on said frame, and a thread guide at the transverse portion of said frame.

6. In a device for winding a tatting shuttle, the combination of a U-shape frame, a trunnion on one of the prongs of said frame, said shuttle being removably journaled on 40 said trunnion, a crank journaled on the other

prong of said frame and having a clutch separably connected to said shuttle, said shuttle adapted to be removed from said 45 trunnion and clutch by the separation of the prongs of said frame, a thread tension device on said frame, a thread guide at the transverse portion of said frame, and a spool holder on said frame.

50 7. In a device for winding a tatting shuttle, the combination of a U-shape frame, the prongs of which are yieldingly drawn toward each other, a trunnion on one of the prongs of said frame, said shuttle being removably journaled on said trunnion, and a crank journaled on the other prong of said frame and having a clutch separably connected to said shuttle, said shuttle adapted to be removed from said trunnion and clutch by the lateral separation of the prongs 60 of said frame.

8. In a device for winding a tatting shuttle, the combination of a U-shape frame, the transverse portion of which is in the form of a spring tending to draw the prongs of 65 said frame toward each other, a trunnion on one of the prongs of said frame, said shuttle being removably journaled on said trunnion, a crank journaled on the other prong of said frame and having a clutch separably connected to said shuttle, said shuttle adapted to be removed from said trunnion and clutch by the separation of the prongs of 70 said frame, a spool holder and a thread tension device on said frame, and a thread guide at the transverse portion of said frame.

75 In testimony whereof I affix my signature in presence of two witnesses.

CHRIS WEBER.
